UNITED STATES PATENT OFFICE.

ALBERT CHARLES DAVIS, OF LIVERPOOL, ENGLAND.

ICE-MAKING APPARATUS.

1,414,330.

Specification of Letters Patent. Patented Apr. 25, 1922.

Application filed October 24, 1921. Serial No. 510,123.

To all whom it may concern:

Be it known that I, ALBERT CHARLES DAVIS, a subject of the King of England, residing at Bootle, Liverpool, in the county of 5 Lancaster, England, have invented new and useful Improvements in or Relating to Ice-Making Apparatus, of which the following is a specification.

This invention relates to ice manufacturing apparatus, and has for its object to provide a new or improved construction of tank, which, for a given ground area occupied shall be of large ice-making capacity, and wherein ice in blocks of desired size or sizes 15 may be produced.

Broadly, my invention is characterized by the provision in a suitable tank of columns or uprights, "freezing" coils supported by said columns or uprights, and plates removably connected to and positioned by said columns or uprights, so that a plurality of moulds, chambers, or compartments are formed, some, or all of which plates constitute "freezing" walls for said coils.

In a preferred mode of removably or detachably connecting said plates with said columns or uprights, longitudinal socket grooves, cavities, or recesses are formed or provided in the latter, in which ends or sides 20 of said plates are adapted to fit and slide; and it is preferred that said longitudinal sockets of the columns or uprights shall be formed at such an angle or inclination that when said plates are assembled and positioned, moulds, chambers or compartments of tapering shape or configuration are formed, so that ice blocks formed therein may, after the "thawing" of the tank, be 25 readily withdrawn therefrom.

Further, the construction and arrangement of the freezing coils and said columns or uprights are preferably such that the coil enclosing wall plates, when positioned in the tank, are in close contact with the top and a 30 short distance from the bottom of the coils.

I will further describe my invention with the aid of the accompanying sheets of explanatory drawings, which illustrate, by way of example only, one mode of embodying 35 the same.

In said drawings:—

Fig. 1 is an elevation, broken away in part in order to expose the interior, of a portion

of an ice manufacturing tank embodying my improvements; and

Fig. 2 is a transverse section viewed at right angles to Fig. 1.

Figs. 3, 4, and 5 are, respectively, elevation, end view, and plan, of the freezing coil unit removed from the tank, and Fig. 6 is a 60 plan of a tank complete.

Fig. 7 is a plan, drawn to an enlarged scale as compared with the preceding figures, of an ice mould, chamber, or compartment.

Figs. 8, 9, and 10 are detached views of a 65 pair of the columns or uprights, Figs. 8 and 9 being elevations taken at right angles to each other, and Fig. 10 a plan.

Referring now to the drawings, *a* designates a tank constructed of wood, or other suitable 70 material, and *b*, *b* represent columns or uprights which are disposed in pairs so formed that when assembled together circular apertures *c* are provided wherein freezing coils *d*, *e* arranged on a duplex system (that is the 75 freezing is effected by means of two refrigerant mediums) are effectively supported. In said columns or uprights *b* there are also formed longitudinal grooves, cavities or recesses *f*, *f*, *f*, *f*, constituting sockets for the 80 reception of the ends or sides of iron or steel plates *g* which are slid into position from the top of the columns and so do not require to be secured by bolts, or the like. Said plates are, therefore, readily removable when 85 desired, as, for the purpose of inspection, cleaning or testing of the coils. Said column or upright slots *f* are inclined as shown in order that moulds, chambers or compartments *b* of tapering shape or configuration 90 are created for the purpose of facilitating the withdrawal of the ice blocks formed therein.

Said coils *d* and *e* are so bent as to form flat grids, the coil components being interlaced one with the other. The freezing operation is effected by the circulation of suitable gaseous refrigerant, such as ammonia, or carbon di-oxide through one of the coils of each unit and brine through the other, and preferably in opposite direction to that of the flow of gas which on leaving the tank passes into a suitable brine cooler and from thence, through the compressor or other machine, to the condenser; the refrigerant gas 100 after passing through the coils enters the 105

brine cooler where it extracts heat from the brine before reaching the refrigerator machine. The cold brine is circulated from the cooler through the appropriate coil components of the grids and back to the brine cooler to be re-cooled by the refrigerant gas.

In an alternative mode of working, the gaseous refrigerant may be passed through each coil of the grid unit, or brine may be passed through each coil.

By appropriate dispositions of said vertical columns or uprights *b* and the use of plates *g* of suitable dimensions, ice blocks of any desired size may be formed.

15 *i, i* indicate thawing-off coils, but which may be utilized for freezing in conjunction with a brine coil *d* or *e*.

There are laid in the compartments *b*, floor plates *k* which cover the coils *i*.

20 When the ice blocks are formed and are required to be removed from the compartments *b*, the cold brine which during the freezing process has been circulated through the brine coil *d* or *e*, is shut off and warm brine is permitted to circulate through said brine coil and pipes *i*.

It is, of course, to be understood, that I do not confine myself to the use of the hereinbefore described duplex coil system, as coil units embodying one coil or any other suitable number of coils may be employed.

What I claim as my invention and desire to secure by Letters-Patent is:—

1. In ice manufacturing apparatus, a tank, 35 a plurality of pairs of uprights disposed within said tank, parallel freezing coils supported between and by the uprights of each pair, and a plurality of freezing plates, each upright having one vertical edge portion of each of four plates removably connected 40 thereto so that a plurality of built-up compartments are formed, each compartment being defined by four of said plates with the plates of each compartment spaced from the plates of adjacent compartments.

2. In ice manufacturing apparatus a tank, a plurality of built-up molds within said tank consisting of vertical posts arranged in pairs and back to back and each having a lengthwise groove in each side thereof and a pair of lengthwise grooves in the front thereof, and freezing plates slipped into said grooves in said posts so that the plurality

of molds are formed with the walls or freezing plates of each mold spaced from the walls 55 of the remaining molds.

3. In ice manufacturing apparatus a tank, a plurality of built-up molds within said tank consisting of vertical posts arranged in pairs and back to back and each having a lengthwise groove in each side thereof and a pair of lengthwise grooves in the front thereof, and freezing plates slipped into said grooves in said posts so that the plurality of molds are formed with the walls or freezing 65 plates of each mold spaced from the walls of the remaining molds, all of said grooves being inclined slightly to the vertical so as to position all walls of each mold in upwardly diverging relation. 70

4. In ice manufacturing apparatus a tank, a plurality of built-up molds within said tank consisting of vertical posts arranged in pairs and back to back and each having a lengthwise groove in each side thereof and a 75 pair of lengthwise grooves in the front thereof, freezing plates slipped into said grooves in said posts so that the plurality of molds are formed with the walls or freezing plates of each mold spaced from the walls 80 of the remaining molds, and thawing-out coils positioned in the spaces between the end walls or freezing plates of adjacent molds.

5. In ice manufacturing apparatus, a tank, a plurality of pairs of uprights disposed 85 within said tank, parallel freezing coils supported between and by the uprights of each pair, a plurality of freezing plates, each upright having one vertical edge portion of each of four plates removably connected 90 thereto so that a plurality of built-up compartments are formed, each compartment being defined by four of said plates with the plates of each compartment spaced from the plates of adjacent compartments, said freezing coils being parallel and each lying between the adjacent side plates of a plurality of compartments, and thawing-out coils between the end walls of adjacent compartments. 95

In testimony whereof I affix my signature in the presence of two witnesses.

ALBERT CHARLES DAVIS.

Witnesses:

JOHN H. WALKER,
WILLIAM PIERCE.
